ATTORNEY

UNITED STATES PATENT OFFICE.

RUDOLPH WILTEIN, OF PROCTOR, COLORADO.

SHOE FASTENER.

1,409,327.

Specification of Letters Patent. Patented Mar. 14, 1922.

Application filed October 31, 1921. Serial No. 511,563.

To all whom it may concern:

Be it known that I, RUDOLPH WILTEIN, a citizen of the United States, residing in the city of Proctor and State of Colorado, have 5 invented new and useful Improvements in Shoe Fasteners, of which the following is a specification, reference being had to the accompanying drawings.

This invention is a shoe fastener, and the 10 object is to provide a simple and efficient means, which may be readily incorporated upon any shoe provided with the ordinary eyelets along the two edges of the frontal opening, and which will facilitate the fastening and unfastening of the shoe.

In the drawings:

Figure 1 is a frontal elevation of a shoe 20 equipped with my improvement, the flaps being unfastened at the top and fastened at the bottom.

Figure 2 is a detail of one of the wire hook fasteners.

Figure 3 is an edge view of one of the 25 flaps, showing the arrangement of the latch cord.

The invention consists in running a latch cord 1 in and out of the eyelets 2 of the flaps 3 of the shoe 4, so as to present outwardly along the edges of the flaps 3 a series of 30 loops 5. The upper ends of the latch cord are knotted as shown at 6, to prevent their pulling out, or are fastened in any conven-

ient way. Wire hook fasteners 7, each made of a simple length of wire, are provided. In forming these fasteners, the wire is bent 35 upon itself to a substantially U-shaped form, the two free ends of each fastener are crimped to form eyelets 8 to engage one of the loops 5 at one side, while the other end of the fastener is bent to form a hook 9 adapted to releasably engage the opposite one of the loops 5, and thus fasten the shoe.

While I have herein described a certain specific method of constructing and assembling the elements of my invention, it is understood that same may be varied in minor details, not departing from the spirit of my invention as defined in the appended claim.

I claim:

A shoe fastener for eyeleted shoes, comprising a latch cord looped in and out through the shoe eyelets; and wire hook fasteners to releasably connect the loops along each of the flaps, each said fastener being made of a single piece of wire bent U-shaped 55 with the free ends formed into eyelets and engaging one of the loops at one side, while the other end is formed into a hook for releasably engaging the opposite loop.

RUDOLPH WILTEIN.
